US0D1060285S

(12) **United States Design Patent** (10) Patent No.: **US D1,060,285 S**
(45) Date of Patent: ** Feb. 4, 2025

(54) **PORTABLE WATERPROOF TV**

(71) Applicant: **Kontech Electronics Co., Ltd.**,
Shenzhen (CN)

(72) Inventor: **Zhiwei Zou**, Shenzhen (CN)

(73) Assignee: **KONTECH ELECTRONICS CO., LTD.**, Shenzhen (CN)

(**) Term: **15 Years**

(21) Appl. No.: **29/882,637**

(22) Filed: **Jan. 17, 2023**

(30) **Foreign Application Priority Data**

Nov. 30, 2022 (CN) 202230803201.0

(51) LOC (15) Cl. **14-03**
(52) U.S. Cl. **D14/126**

(57) **CLAIM**

The ornamental design for a portable waterproof TV as shown and described.

DESCRIPTION

FIG. 1 is a front perspective view of a portable waterproof TV showing my design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures depict portions of the portable waterproof TV that form no part of the claimed design.

1 Claim, 8 Drawing Sheets
